BLOWOFF VALVE FOR LOCOMOTIVE
BOILERS

Charles Ocker, New Smyrna Beach, Fla.

Application June 26, 1947, Serial No. 757,244

4 Claims. (Cl. 251—65)

1

Generically this invention relates to valves in general, but it more particularly is directed to a blow-off valve of the sludge removal type for a locomotive boiler.

This application is a continuation in part of my pending application titled Blow-Off Valve for Locomotive Boilers, Serial No. 491,084, filed June 16, 1943, now abandoned.

During operation of a locomotive, feed water is continuously fed into its boiler with a consequent introduction of entrained foreign matter called "sludge" and in order that the boiler may be maintained in efficient operating condition and it has been prevalent to employ what is known as a blow-off valve to intermittently or otherwise effect removal of the sludge at substantially the same rate as it is introduced. However, the boiler pressure tends to retard the movement of the valve parts, and by reason of the movable parts becoming fouled by particles of such foreign matter it is frequently impossible to close the valve, thereby causing a complete shutdown of the locomotive.

Therefore, one of the principal objects of this invention is the provision of a locomotive blow-off valve comprising a one-piece body portion having a valve chamber extending at right angles to the axis of said body portion, a valve block unit including a movable valve member and a flow aperture, slideable in said chamber, and means for effecting equalization of the boiler pressure within said chamber with respect to said unit and its valve member to effect the free and easy operation thereof to valve open and closed position and prevent sticking of said parts especially in open position.

Another principal object of this invention is the provision of a valve adapted to operate under high boiler pressures, and also under low pressures, providing a valve block unit having an opening therethrough and a valve chamber, a spring controlled valve member mounted in the chamber, said member automatically seating in complete cut off position when the unit is in valve closing position and when in open position providing a full volume discharge and eliminating the choking effect of the globe type valve and possibility of metal or other extraneous particles fouling the latter.

A further important object of this invention is the provision of a valve of this type, the main

2

body of which is cast with a chamber extending beyond opposite sides thereof, a valve housing unit slideable in said chamber, a resiliently mounted auxiliary valve member floatingly seating in said unit, and a steam or sludge discharge port extending through the unit, means in connection with said unit for equalizing the boiler pressure thereon to effect easy operation of said unit and at the same time utilizing the boiler pressure to effect positive seating of said valve in valve closing position.

Another object of this invention is the provision of a valve of this character including an elongated chamber, a one-piece slideable valve unit having a spring controlled movable floating valve member mounted therein, said movable valve member being so constructed that it will not catch or hang during the slideable movement of the unit from valve opening to valve closing position, a valve stem connected to said unit, said parts being removable from the valve body without disturbing or necessitating removal of the body, and said valve stem being readily removable and replaceable with respect to the valve unit.

Another important object of this invention is the provision of a valve of this character including an elongated chamber having aligned inlet and outlet passages and adapted to operate under boiler pressures, a valve block unit having an opening therethrough adapted to register with said inlet and outlet passages when in valve open position, said valve being formed with a cavity in its under surface adapted to register with said outlet passage when said block is in valve closing position, a floating valve member mounted in said cavity, spring means mounted in said cavity seating on the bottom thereof and on said valve, a fluid passage encircling said block and communicating with said cavity, whereby upon movement of the block to valve closing position the pressure on the upper surface of the block forces it downwardly against the action of the spring sufficiently to direct the fluid over said block to and through said passage to said cavity so that the pressure will be equalized on the upper and lower surfaces of the block, and the balancing pressure in the cavity supplemented by the stored energy in the spring imparts floating characteristics to the valve block permitting its easy and ready withdrawal.

Another important object of this invention is

the provision of a blow-off valve of this type, the main body of which is cast with a chamber extending beyond opposite sides thereof having aligned inlet and outlet fluid passages, a valve block unit having upper and lower plane surfaces including a fluid passage and a valve cavity in its lower side, a floating valve member seating in said cavity and having no direct connection with the valve block, spring means in said cavity for maintaining said valve in sealing position with respect to said outlet opening, and an encircling steam or fluid passage around the block adapted to effect equalization of pressure on opposite sides thereof tending to floatingly position it and at the same time maintain said floating valve in valve closing position, not only effecting the easy reciprocal movement of the block, but providing a definite escape passage for the steam or fluid and sludge as the block is moved to closed position, and, additionally, causing any foreign matter in the chamber to be cleared therefrom through said passage by the intermittent discharge of the steam at high velocity through the restricted opening between the lower edge of passage 21, and the upper end of outlet opening 13. In this connection it is to be noted, as the floating valve block attains its closing position, pressure upon the block depresses the latter and materially reduces the escape space for the steam to outlet opening 13, so that the steam will flow through this reduced space at high velocity and thus function to scavenge the chamber. This construction permits the valve block to readily move to complete valve closing position without any fluid cushioning effect which would otherwise be present.

Another important object of this invention is the provision of a blow-off valve of this type, the main body of which is cast with a chamber extending beyond opposite sides thereof having aligned inlet and outlet fluid passages, a valve block unit having upper and lower plane surfaces including a fluid passage and a valve cavity in its lower side, a floating valve member seating in said cavity, spring means in said cavity for maintaining said valve in sealing position with respect to the said opening, and additional means in connection with said block cavity for supplementing the action of said spring in one direction maintaining the valve seated, and said spring also reacting in conjunction with said supplemental means to effect equalization of the fluid pressure on said block when it is in passage closing position to render it easily removable.

Another important object of this invention is the provision of a blow-off valve of this type, the main body of which is cast with a chamber extending beyond opposite sides thereof having aligned inlet and outlet fluid passages, a valve block unit having upper and lower plane surfaces including a fluid passage and a valve cavity in its lower side, a floating valve member seating in said cavity, spring means in said cavity for maintaining said valve in sealing position with respect to said outlet opening, and means surrounding said opening forming a seat for said valve, the construction and arrangement of said valve and valve seat being such that upon removal of said seat member the valve may be readily removed and replaced without necessitating removal of the valve block and while said block is in valve closing or seating position.

A further object of this invention is the provision of a blow-off valve of the character described wherein the exterior valve parts such as

the bonnet and operating handle retaining ring may be locked against rotary movement by simply being placed in seating position and whereby the operating handle will be supported in proper operating position, said bonnet and coacting parts adapted for threaded connection, thus eliminating bolted connections and enabling the valve to be readily disassembled and reassembled as desired.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a side elevation of the valve operatively connected to the boiler with parts in fragmentary section.

Fig. 2 is a plan view of the valve in closed position and in dotted lines to open position.

Fig. 3 is a vertical longitudinal section of the line 3—3 of Fig. 2.

Fig. 4 is a horizontal section on the line 4—4 of Fig. 3.

Fig. 5 is a fragmentary vertical section on the line 5—5 of Fig. 4.

Fig. 6 is a vertical longitudinal section showing the parts in complete open or discharge position.

Fig. 7 is a fragmentary transverse vertical section on the line 7—7 of Fig. 6.

Fig. 8 is a fragmentary transverse vertical section on the line 8—8 of Fig. 2.

Fig. 9 is a perspective inverted view of the valve housing.

Fig. 10 is a fragmentary perspective view of the valve stem removed from the housing.

Fig. 11 is a detail inverted side elevation of the valve showing one of the steam openings.

Fig. 12 is a detail top plan view of Fig. 11.

Fig. 13 is a horizontal section on the line 13—13 of Fig. 11.

It has been prevalent in connection with locomotive blow-off valves for effecting the removal of sludge, or contaminated boiler water, for the valve operating under high boiler pressure to become fouled and stuck causing a complete shutdown of the engine and removal of the valve body in order to gain access to the operating parts for cleaning, replacement, and the like, and it was to overcome the disadvantages of such valve structures and to provide a blow-off valve, including a valve body having a valve chamber, a slideable valve unit including a movable valve member housed therein, so constructed that the operating parts exteriorly and within the valve body can be easily removed and replaced without removal of the valve proper, and constructed to prevent clogging of the valve by extraneous particles accumulating therein and to prevent such accumulation, and designed to equalize the boiler pressure within the valve body and on opposite sides of the valve unit to render it freely operable from open to closed positions, and since in effect the movable valve member in closed position constitutes a continuation of the bottom wall of said chamber, when in such position the pressure thereon will maintain it closed and at the same time effect a reactive equalizing pressure on said unit, that I designed the device forming the subject matter of this invention.

In the illustrated embodiment characterizing

this invention there is shown a valve A and a locomotive boiler B.

A valve nipple connection 1 formed with a hexagonal body portion 2 terminating at one end in a reduced threaded portion 3 and at the opposite end in a similar reduced threaded portion 4, the end 3 being adapted for threaded engagement in opening 5 formed in the bottom of boiler B and effecting communication with the boiler feed or sludge water 6. While the nipple fitting 1 is described as threadedly connected to the boiler B, it may be connected by a boiler flange fitting or in any suitable manner as desired.

The locomotive sludge blow-off valve A is formed with a valve body portion 7 formed with a threaded socket 8 at its upper end adapted to receive the threaded end 4 of nipple 1 and by means of which, in the present instance, it is attached to the boiler B. Said body at its lower end is formed with a threaded socket opening 9 terminating in a lateral seat 10 and an annular flange 11 surrounding said seat. Said body 7 is formed with a central bore inlet opening 12 and a similar outlet opening 13 and is formed intermediate the openings 12 and 13 with a substantially rectangular laterally or horizontally extending chamber 14 extending beyond opposite sides of the body portion 7, formed at one end with a rounded end 15 and terminating at its other end in an annular flange 16 exteriorly threaded as at 17.

A valve gate block unit 18 is adapted for slideable or reciprocating movement in said chamber 14 and is rounded at one end as at 19 conforming to the rounded end 15 of said chamber, and is formed with a flat end surface 20 at its other end. Adjacent end 19 it is formed with a flow or discharge opening 21 adapted when in open position to register with inlet opening 12 and outlet opening 13 to form a continuous unobstructed passage for the flow of said boiler water 6 from the boiler (Figs. 3 and 6). Said block 18 is formed in its lower surface with an annular valve cavity or chamber 22, said chamber being counterbored as at 23 to form a valve seat 24 and at 45 diametrically opposite sides, said block is formed with an opening 25 extending from the lower surface to seat 24 and each opening 25 is formed with a smaller opening 26.

An annular floating valve 27 is mounted in chamber 22 of a thickness substantially corresponding to the depth of the counterbored opening 23 so that when in engagement with seat 24 it will not extend beyond the surface of block 18. Said valve is formed with a flange 28 adapted to extend substantially to the bottom of chamber 22 when valve 27 is in engagement with seat 24 and flange 28 is formed adjacent its upper edge with an annular channel 29 provided in the present instance with four equi-spaced openings 30 extending therethrough.

Also valve 27 is formed with an upstanding centrally positioned lug 31 which has suitably secured thereto a spirally wound conically shaped compression coil spring 32 which is adapted to seat on the bottom of cavity 22 (Fig. 5) and tending to normally project valve 27 beyond the lower surface of block 18 and into engagement with the lower chamber wall and its seat 13' surrounding outlet 13, when in valve closing position.

It will be observed that the threaded end 16 of nipple connection 14 when engaged in opening 9 flush with the bottom wall of chamber 14 surrounds outlet opening 13 and forms a seat 13' for the auxiliary or floating valve 27. To

remove said valve it is only necessary to unscrew nipple 14, whereupon the valve will drop out or be expelled by spring 32, and it may be replaced or substituted by simply putting the valve in opening 9 and replacing the threaded end of said nipple therein. This is extremely important since the valve may be removed and replaced in a few minutes, which otherwise would require several hours with the locomotive out of service.

Extending completely around the block 18 substantially central of its height, intersecting the openings 26 and terminating at each end in the T or bayonet slot opening 33, is the boiler pressure equalizing groove 34 for a purpose that will directly more fully appear.

The surface of valve 27 is formed with an annular slightly raised portion 35 and having its peripheral edge beveled as at 36 so that said valve may be moved into and out of closed or seating position with respect to outlet opening 13 (Figs. 3 and 5) without catching or binding and also prevents binding or clogging of the valve with respect to the lower wall of chamber 14 by the temporary presence of extraneous matter during its reciprocal movement from open to closed position as will be apparent.

It will be further noted with respect to valve block 18 adapted for slideable movement in chamber 14 that the openings 25 and 26 allow the boiler pressure to build up in chamber 22 and force the valve 27 into seating position when moved to valve seating or closing position, at the same time reacting against block 18 and with the pressure equalizing groove 34 effecting equalization of the boiler pressure within the valve body, that is, chamber 14, and with respect to valve block 18 to effect the desired free action of said block therein. Not only this, but the intermittent steam pressure within chamber 14 and through valve chamber 22 cleans and keeps said parts free from accumulation of extraneous matter and prevents clogging and binding of the movable parts resulting in a stuck valve, and has been prevalent in valve structures heretofore in use.

With further reference to the boiler pressure equalizing groove 34, it will be noted that upon movement of the valve block 18 to valve closing position the pressure on the upper surface of the block forces it downwardly against the action of the spring 32 sufficiently to permit the fluid to flow over said block and to and through said groove to said cavity 22 so that the pressure will be equalized on the upper and lower surfaces of the block, and the balancing pressure in the cavity supplemented by the stored energy in the spring imparts floating characteristics to the valve block thereby permitting its easy operation.

This structural arrangement including said groove or encircling steam passage around the block, not only effects the easy reciprocal movement of the block, but provides a definite escape passage for the steam or fluid and sludge as the block is moved to closed position, and, additionally, causes any foreign matter in the chamber to be cleared therefrom through said passage by the intermittent discharge of the steam, permitting the valve block to readily move to complete valve closing position without any fluid cushioning effect which, practice has demonstrated, would otherwise be present.

Adapted to seat on the end face of flange 16 is a bonnet structure 37 formed with a dowel pin or lug 38 adapted to project in opening 39 which holds the bonnet in position and against

rotation. Said bonnet is formed with a flange 40 provided with an annular seat 41 on which is adapted to seat a bonnet retaining cap nut 42, threadedly engageable with thread 17 to retain the bonnet in rigid and sealing position thereon. Said bonnet is formed with an annular seat 43 on which is adapted to seat the link supporting ring 44 and suitably formed in and projecting above seat 43 is a dowel or lug 45 adapted to project through opening or recess 46 in ring 44 to maintain said link support against rotation. This pin is so positioned with respect to the circumference of the seat or the opening 46 with respect to the inner wall of the ring as to place the link 47 in position to support the operating lever 48 in the desired operating position. Bonnet 31 is formed substantially coincident with the surface of said ring 44 with a reduced threaded portion 49 adapted to threadedly engage the hexagonal nut 50 which when tightened thereon locks the supporting ring 44, in position. Bonnet 31 terminates in a further reduced threaded end portion 51 and on which is threadedly mounted a valve stem packing nut 52 containing the packing 53. It will be understood that valve stem 54 extends through said bonnet 31 and valve stem packing nut 52, and is formed at its inner end with an annular groove 55 and a square or rectangular end piece 56 adapted for engagement in slot 33 of valve block 18 and which constitutes one wall of the groove and with an enlarged portion 57 adjacent said groove the free edge of which is beveled as at 58, and constitutes a valve seat.

The inner face of bonnet 31 is countersunk as at 59 to receive the enlarged portion of valve head 57 and the bottom of said opening 59 is concaved as at 60 to form a seat for the complementary beveled face 58, not only forming a stop to limit the movement of valve stem 54 in valve opening direction but effecting a seal for chamber 14 when the valve stem is in valve opening position. Link 47 is bifurcated at one end as at 61 to receive the upstanding ear 62 of ring 44 to which it is pivotally connected by pin 63 secured by cotter pin 64 and the other end of link 47 is similarly bifurcated as at 65 to receive the end 66 of lever 48 secured therein by pin 63 and cotter pin 64 similar to the connection at its other end. Lever 48 is formed with an enlarged or thickened portion 67 formed with a substantially elongated slot 68 adapted to receive the reduced end 69 of valve stem 54 pivotally connected therein by pin 70 extending therethrough, and formed with an opening 71 adapted to receive a cotter pin 64, or secured in any suitable manner as will be well understood. The lever 48 is formed at its free end with opening 72 and in which may be connected any suitable reach rod linkage or operating medium 73 extending to the cab of the locomotive or elsewhere for operation by the engineer as will be well understood.

A nipple connection 74 is formed with a hexagonal body portion 75 terminating at one end in a reduced threaded portion 76 adapted for threaded engagement in opening 9 of the valve body 7 and with the complementary valve seat or shoulder 77 engageable with seat 10, and with an offset flange seat 78. Adapted to seat on flange seat 78 is a copper or other suitable gasket 79 forming a steam seal connection with flange 11. It will be well understood, that suitable gaskets may be interposed between the normally meeting faces of any of the respective fittings as desired. Nipple 74 terminates at its free end in an annular flange 80 exteriorly threaded as at 75

81. The end face 82 of nipple 74 surrounding the bore 83, communicating with outlet 13, is concaved or rounded as at 84 to form a seat for the complementally formed rounded head 85 of body member 86 of a union fitting assembly 87. Said body member 86 is threaded as at 88 to receive the threaded end 89 of a fluid or discharge pipe 90, and is formed with an annular lateral flange 91. An apertured hexagonal internally threaded screw cap member 92 is adapted to fit over member 86 in engagement with flange 91 and to threadedly engage flange 80 to sealingly seat head 85 in engagement with seat 84. Said union fitting comprises the members 86 and 92.

15 With further reference to valve stem 54 it will be understood that the seating of head 57 in opening 59 and the coacting seats 58 and 60 not only provide a stop for the open position of the valve block and prevent undue strain on the T-head of said valve stem 54 when in valve open position but effects a steam seal for chamber 14. Such construction constitutes an important feature, since when the valve block is brought to full valve open position the seating of valve stem head 57 forms a steam seal, and the valve stem can be repacked as at 53 under full boiler pressure by placing a cut-off valve 90' in the outlet pipe 90 or by applying a suitable fitting to the end of said discharge or outlet pipe 90, preferably with 20 a drain valve in it to relieve the pressure in the pipe after the packing is completed, and which repacking operation requires only a few minutes. Usually this operation requires that the steam and water be drained from the boiler, and after 25 the repairs are made the boiler must be refilled with water and fired up to service pressure. It usually takes about six hours to complete the whole operation, and which is obviously an expensive proposition.

30 40 While the operation of the device would seem to be clear from the above description, it might be well to further state that when the valve is operatively connected to the boiler and in communication with the boiler feed or sludge waters 6 as shown in Figs. 1 and 3, operation of the lever 48 to valve closing position places valve block 18 in the position shown in Fig. 3 with valve 27 in seating position with respect to outlet 13 and the boiler pressure admitted into chamber 14 around block 18 and into valve chamber 22 maintains said valve in seating position and, by means of the formation of said valve block such boiler pressure is equalized in said chamber 14 thereby permitting easy manipulation of said block to valve opening and closing positions as heretofore referred to. Movement of lever 48 in the opposite direction moves valve stem 54 outwardly and, head 57 seating in opening 59 not only limits the movement of block 18 and positions opening 21 in alignment with inlet opening 12 and outlet opening 13, but head 57 constitutes a valve stem seal with respect to chamber 14. It will be seen that the limit of movement of valve stem 54 in one direction moves valve block 18 to complete open position, and its limit of movement in the opposite direction positions valve 27 in valve closing position. It is therefore apparent that valve A may be instantly operated as desired to opened or closed positions to discharge or cut off the flow of sludge therethrough.

45 50 In this connection it will be observed that if desired, a continuous and regulated discharge sludge flow may be effected by simply maintaining operating lever 48 at any point of adjustment

of passage 21 of valve block 18 from complete open to closed position with respect to inlet 12.

It will be further noted that when the fluid passage 21 of valve block 18 is in registration with the aligned inlet and outlet passages and valve stem head 57 is in engagement with seat 60 a fluid seal surrounding the valve stem is provided for chamber 14, so that when the fluid flow through outlet extension 98 is cut off by member 90' the pressure in said chamber will maintain said head 57 seated, and the removal of and repacking of the packing assembly or cap unit 52 may be effected under prevailing or full boiler pressure. Upon completion of the packing operation, all that is necessary to restore the boiler or locomotive to normal operating condition, is the opening of the cut-off element 90'. While the assembly A has more particularly been described as a blow-off sludge valve for locomotive boilers, it is to be understood that it is equally applicable to other types of boilers as well.

It will be apparent that I have designed a boiler valve assembly including a body or casing having aligned inlet and outlet fluid passages, a valve block including a valve stem, said block being mounted within the casing and slidable in a chamber intercepting its passages, means in connection with said block for equalizing the fluid pressure on said block to render it freely slidable, and an end detachable and readily demountable chamber closure or bonnet assembly including valve operating lever supporting and locking means, a removable valve stem packing retaining unit or assembly, and means for effecting replacement of the packing under prevailing boiler pressure, said valve assembly being simple in construction, manufacturable at a reasonable cost, easily installable, and efficient for the purposes intended.

Although in practice it has been found that the form of the invention illustrated in the accompanying drawings and referred to in the above description as the preferred embodiment is the most efficient and practical, yet realizing that conditions concurrent with the adoption of the invention will necessarily vary, it is well to emphasize that various minor changes in details of construction, proportion and arrangement of parts, may be resorted to within the scope of the appended claims without departing from or sacrificing any of the principles of the invention.

Having thus described my invention, what I desire protected by Letters Patent is as set forth in the following claims:

1. In a valve assembly, a casing formed with aligned fluid passages, a valve block mounted within the casing and slidable in a chamber intercepting its passages, said block being mounted within the chamber for limited movement transversely and vertically with respect to its sliding movement and including a fluid passage and a valve section alternately operable into registering position relative to said fluid passages and pressure means in connection with said block for positioning the block for easy reciprocatory movement said pressure means including a source of fluid under pressure and a plurality of passageways formed exteriorly and interiorly of the block for directing said fluid around and interiorly of the block to space the latter from the walls of said chamber, whereby said block during its sliding movement is adapted to float within said chamber when subjected to fluid pressure.

2. In a valve assembly, a casing formed with aligned fluid passages, a valve block mounted

within the casing and slidable in a chamber intercepting said passages and having inlet and outlet openings in respect to said passages, said block being mounted within the chamber for limited movement transversely and vertically with respect to its sliding movement and having upper and lower plane surfaces and including a fluid passage therethrough, and a valve cavity opening through its lower plane surface, a valve member seated in said cavity adapted to close said outlet opening, and pressure means in connection with the upper and lower plane surfaces of said floating block, whereby said block may be readily moved to valve closing position said pressure means including a source of fluid under pressure, and a plurality of passageways formed exteriorly and interiorly of said block, said passageways being in communication with said fluid under pressure and for directing the fluid in enveloping relation with respect to said block and into said cavity to space the block from the defining walls of said chamber, whereby said block during its movement is adapted to float within said chamber when subjected to fluid pressure.

3. In a valve assembly, a casing formed with aligned fluid passages, a valve block mounted within the casing and slidable in a chamber intercepting its passages and having inlet and outlet openings with respect to said passages, said block being mounted within the chamber for limited movement transversely and vertically with respect to its sliding movement and having upper and lower plane surfaces and including a fluid passage therethrough, said block being formed with a valve cavity opening through in its lower side, a valve member seating in said cavity adapted to close said outlet opening, said fluid passage and valve member being alternately operable into registering position with respect to said inlet and outlet openings, spring means in said cavity for maintaining the valve member in sealing position with respect to said outlet opening, and additional means in connection with said block for supplementing the action of said spring means, said additional means including a source of fluid under pressure and a plurality of passageways formed in said block and extending exteriorly and interiorly thereof and into enveloping relation with respect to said block and into said cavity to space said block from the defining walls of said chamber, whereby said block during its sliding movement is adapted to float within said chamber when subjected to fluid pressure.

4. In a valve assembly, a casing formed with aligned fluid passages and an elongated chamber intercepting the passages, the chamber having inlet and outlet openings in connection with said passages, a valve block adapted to float within the chamber when subjected to fluid pressure, said block being slidably mounted within said chamber and constructed and arranged for limited movement transversely and vertically with respect to its sliding movement, said valve block including cut-off and fluid passage portions and being shiftable alternately to open and closed positions, said cut-off portion having a solid upper surface and a cavity in its under surface, a valve member seated in said cavity, a removable seat for said valve member, yieldable means in said cavity in connection with said valve member tending to project it beyond the under surface of said block into engagement with the lower chamber wall and said seat, and means in connection with said block and cavity adapted to

11

maintain said valve member seated with respect to said outlet opening and to entrap fluid in said chamber when the block is in passage closing position tending to float said block so that its 5
slidable movement may be easily effected, said means including a source of fluid under pressure, a fluid channel formed in the vertical wall of and extending around said block and in communication with said cavity and with said source of fluid for directing said fluid in enveloping 10 relation with respect to and interiorly of said block, said channel additionally serving to release fluid trapped in said chamber to permit the

12

movement of said valve block to valve closing position.

CHARLES OCKER.
